(57) **CLAIM**

The ornamental design for a hinge pin, as shown and described.

DESCRIPTION

FIG. 1 is a perspective view of a hinge pin, showing my new design;

FIG. 2 is an exploded perspective view thereof;

FIG. 3 is a front elevational view thereof;

FIG. 4 is a rear elevational view thereof;

FIG. 5 is a left-side elevational view thereof, the right-side elevational view being a mirror image thereof;

FIG. 6 is a top plan view thereof;

FIG. 7 is a bottom plan view thereof; and,

FIG. 8 is a cross-sectional view taken in the direction of line 8-8 in FIG. 3.

The broken lines in the figures depict environmental matter that forms no part of the claimed design.

1 Claim, 4 Drawing Sheets
